(57) **CLAIM**

The ornamental design for an axial ridged housing portion of a positive displacement pump assembly, as shown and described.

DESCRIPTION

FIG. 1 is a front/right side isometric view of an axial ridged housing portion of a positive displacement pump assembly showing my new design;

FIG. 2 is a front elevational view;

FIG. 3 is a rear elevational view;

FIG. 4 is a right side elevational view;

FIG. 5 is a left side elevational view;

FIG. 6 is a top plan view; and,

FIG. 7 is a bottom plan view.

The broken line showing of elements is included for the purpose of illustrating environmental matter and forms no part of the claimed design.
